UNITED STATES PATENT OFFICE.

CHRISTIANNA HENDRICKSON, OF NEW YORK, N. Y.

DESIGN FOR A LAMP.

No. 39,983.

Specification for Design.

Patented May 11, 1909.

Application filed March 6, 1909. Serial No. 481,858. Term of patent 14 years.

To all whom it may concern:

Be it known that I, CHRISTIANNA HENDRICKSON, a citizen of the United States, residing at New York, in the county of New York and State of New York, have invented a new, original, and ornamental Design for Lamps, of which the following is a specification, reference being had to the accompanying drawing, forming part thereof.

Figure 1 is a side elevation of a lamp showing my new design and Fig. 2 is a bottom plan view thereof.

I claim:

The ornamental design for a lamp, as shown.

CHRISTIANNA HENDRICKSON.
